UNITED STATES PATENT OFFICE

163,179

TOOTHBRUSH HOLDER

Benjamin W. Hiller, Chico, Calif.

Application May 18, 1948, Serial No. 146,431

Term of patent 3½ years

(Cl. D4—3)

To all whom it may concern:

Be it known, that I, Benjamin W. Hiller, a citizen of the United States and a resident of the city of Chico, county of Butte, State of California, have invented a new, original, and ornamental Design for a Tooth Brush Holder, of which the following is a specification, reference being had to the accompanying drawing, forming part thereof.

Referring to the drawing:

Fig. 1 is a side elevational view of a tooth brush holder showing my new design;

Fig. 2 is an end elevational view;

Fig. 3 is a top plan view thereof.

I claim:

The ornamental design for a tooth brush holder, as shown.

BENJAMIN W. HILLER.
